UNITED STATES PATENT OFFICE.

XAVIER STIEGLER, OF BAR-LE-DUC, MEUSE, FRANCE, ASSIGNOR TO HIMSELF
AND JULES CARGEMEL, OF SAME PLACE.

FEEDING MECHANISM FOR LOOMS FOR WEAVING SEAMLESS CORSETS, &c.

SPECIFICATION forming part of Letters Patent No. 235,915, dated December 28, 1880.

Application filed September 3, 1880. (No model.) Patented in France May 20, 1880.

To all whom it may concern:

Be it known that I, XAVIER STIEGLER, a citizen of the French Republic, residing in Bar-le-Duc, Meuse, France, have invented certain Improvements in Feeding Mechanisms for Looms for Weaving Seamless Corsets and other Irregular or Gusseted Fabrics, of which the following is a specification.

It is necessary in weaving fabrics where convex or concave places occur to form gussets by weaving in short weft-threads until the desired fullness is produced, and then to draw the unfinished edge of the web into a straight line, that the full-width weaving may be resumed.

In the accompanying drawings, Figures 1, 2, and 3 are diagrams illustrating the fabric in the successive stages of this operation.

A A are the warp-threads, indicated by light lines, and B B are the weft-threads, indicated by heavy lines. Weft-threads, shown at *a a*, are woven entirely across the fabric until the place is reached where the gusset is to be formed. Then shorter weft-threads (shown at *b b*) are woven in until the gusset attains the desired fullness. Fig. 1 shows the fabric after this has been accomplished. Then the batten is brought forward until the reed rests against the last of the short threads and the woven web is released, so that the tension upon the warp draws the unfinished edge forward against the reed, thereby bringing it into a straight line. Fig. 2 shows the fabric after this operation has been performed. Then the weaving of full-width weft is resumed, as shown at *a'* in Fig. 3.

Irregular weaving is distinguished from regular weaving by the fact that in the latter all portions of the woven fabric or web are fed forward uniformly or at an equal speed, while in the former, being woven without uniformity, they must be fed forward at different speeds, the fuller portions being fed faster than the others in proportion as they are woven faster.

In weaving regular goods by power-looms the finished web is wound upon a roller, which takes it up as fast as it is woven; but in weaving irregular or gusseted fabrics it has heretofore been found necessary to feed intermittently, holding the web stationary by a clamp

until a certain amount has been woven, then releasing the clamp and carrying the web forward by the batten to the extreme forward position of the latter, and then giving the clamp a new hold and resuming the weaving. 55 Consequently it has been essential that the batten should recede by the width of a thread as each thread is woven in. In hand-weaving this is easily accomplished, since the play of the batten is not necessarily uniform, being 60 regulated by the hand of the operator; but in power-looms complicated mechanical devices have to be employed to carry back the batten uniformly and at a speed corresponding to the speed with which the weft is filled in, and to 65 carry it forward quickly and to its fullest extent when the web is to be carried forward. To overcome these objections I have devised a feeding mechanism applicable to the ordinary power-loom, which carries forward the 70 web as fast as it is woven, as in regular weaving, and which, after the short threads forming a gusset have been woven in, may be made to release its hold upon the fabric, letting the latter be drawn back to a straight edge against 75 the reed, whereupon it may be moved back and re-engaged with the fabric, and the feeding resumed. Thus the batten has a uniform play, and does not recede as the weft is filled in.

My improved feeding mechanism is illustrated in Figs. 4, 5, and 6 of the accompanying drawings, the forward portion of the loom being also shown in Figs. 4 and 5, but the remainder thereof being omitted, since it is of the usual construction and forms no part of 85 my invention, nor is it essential to elucidate the operation thereof. Fig. 4 is a front elevation. Fig. 5 is a vertical section taken in the plane of the line *xx* in Fig. 4, and Fig. 6 is a sectional detail view on a larger scale. 90

C is the fixed frame of the loom; D, the lay or batten, and c the reed or comb mounted in the latter, all being substantially of the usual construction.

E E' are clamping-bars, between which the 95 fabric (shown in Fig. 5 by the line *d*) may be gripped or clamped. The bar E is preferably faced with leather, rubber, cloth, or other soft or elastic substance over which the fabric passes. The bar E' is arranged above the bar E, and 100

is capable of being pressed forcibly down upon the same, and its lower edge is preferably formed with fine teeth or points to engage the fabric and prevent its slipping. The two bars E E' 5 are capable of motion together toward or from the batten. This may be effected in several ways, the preferable one (shown in the drawings) being by mounting them on a swinging frame, e, which is pivoted beneath on a 10 rock-shaft, f. The bar E is fixed to the frame e, while the bar E' is mounted thereon so as to have a slight vertical motion. Its ends are fixed to the short arms of levers g g, whose long arms are connected, through the medium 15 of links h h, levers i i, and links j j, to levers l l, which carry weights F F. The weights act at great mechanical advantage to force the bar E' down upon the bar E, and are lifted to raise the bar E' by depressing a treadle, m, 20 with the foot, this treadle being fixed to a rock-shaft, n, which ties together the two levers l l.

The devices h, i, j, k, l, and F are preferably duplicated, as shown, though a single set, if arranged centrally, might serve the purpose.

25 The bars E E' are drawn forcibly forward by the following-described mechanism: The frame e is provided with toothed racks p p, which mesh with pinions r r, fixed on a shaft, G, which has bearings in the frame C. The racks 30 may be guided and kept in mesh with the pinions by means of guiding-frames s s, which embrace the shaft G and determine the extent of motion of the frame e. The shaft G bears, near its extremity, a gear-wheel, H, which is 35 loose on the shaft and meshes with any suitable gearing of the loom, a portion of which is shown in Figs. 4 and 5, being lettered tt. This gearing is preferably the same and driven by the same means as that commonly employed 40 in power-looms for operating the cloth-roll or take-up, that roll having been removed from the machine and the shaft G applied in its place. I provide some suitable means for causing the shaft G to rotate with the wheel 45 H when desired, the preferable device for this purpose consisting of a radial arm, I, fixed to the shaft close to the wheel, and fitted with a clutch, J, to engage the periphery of the wheel. The preferable form of this clutch is shown in Fig. 50 6, which is a vertical mid-section. The clutch consists of a clamping-head which overhangs and bears against the rim of the wheel, and has a screw-threaded shank which passes through the end of the arm I and is engaged 55 by a nut which forms part of a handle or lever, K. By turning this handle the screw is drawn back and the rim of the wheel tightly clamped. A device for taking in between the teeth of the wheel may be substituted for the 60 clamp.

The operation is as follows: The frame e stands at first in the position shown in Fig. 5 in dotted lines, its clamping-bars having firm hold of the fabric. If, now, the clutch J be 65 engaged with the wheel H, by turning the lever K the shaft G and its pinions r r will ro-

tate with the wheel in the direction of the arrow in Fig. 5, drawing forward the racks and the frame e until the latter occupies the position shown in full lines. The fabric is thus 70 drawn steadily forward, while the threads a and b are being woven, at a speed corresponding to the rapidity of the weaving. At the completion of the threads for the gusset, or when the frame e has assumed the position shown in 75 full lines, the loom is stopped by the action of the Jacquard mechanism, which governs the weaving in of the thread b or by other suitable means. The batten D will then be moved forward, being assisted by the hand of the operator if necessary, until its reed rests against the last thread, b, Fig. 1, of the gusset, being then in about the position shown by the dotted lines in Fig. 5. The operator then disengages the clutch J from the wheel H, thus 80 freeing the shaft G and frame e, and then, by pressing with his foot on the treadle m, he lifts the clamping-bar E', and thus releases the fabric, which is at once drawn back by the tension of the weights, which stretch the warp 85 until its rear edge is brought into a straight line against the reed c, as shown in Fig. 2. The operator then, while still holding down the treadle, pushes back the frame e into its first position, then releases the treadle, thus 90 permitting the bars E E' to again clamp the fabric, and again tightens the clutch J, when the loom is again started, the weaving of wide weft-threads is resumed, as shown at a', in Fig. 3, and the former operation is repeated. 95 The operation thus proceeds intermittently, the forward motion of the clamping-bars feeding forward the goods as it is woven, and the bars being brought back each time after the weaving of a certain length, usually the distance between two gussets. 100

My mechanism is susceptible of considerable modification without departing from its essential features, as, for instance, the lower clamping-bar might be made the movable one. The 110 two bars might be pressed together by springs instead of weights and levers. The bars might slide forward and backward in guides or ways instead of being borne by a pivoted frame. The forward movement of the frame or bars 115 might be effected by other gearing and connections than those shown. The connecting and disconnecting of the mechanism for moving forward the bars might be effected by other forms of clutches or by any known form 120 of let-off device, and a single bar with teeth to penetrate the goods might be substituted for the clamping-bars. 125

I claim as my invention—

1. A feeding mechanism for looms, consisting of an engaging portion for taking hold of the web, which can be engaged therewith or be disengaged therefrom at will, and which is capable of motion bodily toward and from the batten, in combination with mechanism for propelling it forward or from the batten as the weaving proceeds, and with means for con-

necting and disconnecting it with said propelling mechanism, substantially as and for the purposes set forth.

2. A feeding mechanism for looms, consisting of clamping-bars E E' of suitable construction, capable of motion toward and from the batten of the loom, in combination with means for forcing them together and for separating them, with mechanism for propelling them forward or away from the batten while the weaving is in progress, and with means for disconnecting them from said propelling mechanism, substantially as set forth.

3. In a feeding mechanism for looms, the combination of the pivoted frame e, the clamping-bar E, fixed thereon, the levers g g, fulcrumed to said frame, the clamping-bar E', mounted on said levers, the weighted levers l, suitable connecting mechanism between levers g and l, and the treadle m, whose depression lifts the weighted levers and raises the bar E', substantially as set forth.

4. In a feeding mechanism for looms, the combination of the engaging device for holding the fabric, the frame e, bearing the same, and the rack p, pinion r, shaft G, wheel H, and means for engaging and disengaging said shaft and wheel, substantially as set forth.

5. In a feeding mechanism for looms, the combination of the engaging device for holding the fabric, the frame e, bearing the same, the rack p, the pinion r, the shaft G, the wheel H, the clutch J, and the lever K, substantially as set forth.

In witness whereof I have hereunto signed my name in the presence of two subscribing witnesses.

XAVIER STIEGLER.
